PORTABLE MARKING DEVICE

Werner P. Pohle, Lynn, Mass.

Application May 15, 1951, Serial No. 226,348

4 Claims. (Cl. 299—18)

1

This invention comprises a new and improved device for marking with liquid medium logs, cartons, or other articles, or producing road marks for traffic control, or for any other purpose where marks of the same character are to be repeatedly applied.

The device of my invention is organized to be operated by pressure against the surface to be marked; that is to say, by pressing a projecting pilot element of the device against the surface the desired mark is automatically produced in predetermined location, exact size, and specified intensity. To this end the device is constructed and arranged to measure each charge of liquid marking medium, to deliver the charge as an atomized spray, and to distribute and govern the size of the charge in accordance with the character of the mark desired.

Heretofore marking devices have been known which require a pressure tank for the marking medium or require manually operated pumping mechanism for delivering the charge. While these have been useful in limited fields, they either require the operator to carry heavy equipment or to limit his field of activity, or to operate pumping mechanism, and that frequently results in inaccuracies in locating the marks and increases the physical effort required to manipulate the apparatus. On the contrary, the device of this invention may be preliminarily located accurately in respect to the spot to be marked and then by mere pressure against its surface the mark is accurately applied without otherwise displacing the device and a new measured charge is drawn into operative position in readiness for making the next mark.

These important and advantageous results are achieved in the marking device of this invention which comprises a handle having a piston fixed thereto which has therein a passage for the marking medium, in combination with a cylinder slideable on the piston and forming therewith a valve controlled pressure chamber having an atomizing outlet. Spring means is provided for relatively moving the cylinder and piston to create suction within the chamber and to hold the piston and cylinder into relatively extended position. This means yields in response to pressure exerted through a forwardly extending pilot member causing forcible discharge of the liquid marking medium from the chamber. When pressure is relieved this spring means immediately acts to return the piston and cylinder to their initial position and at the same time to create suction within the chamber, thereby drawing in

2

a new charge preparatory to application of the next mark.

Preferably and as herein shown, the pilot member is adjustably mounted upon the cylinder and thus positively determines the distance between the spray nozzle and the surface to be marked. Since the marking medium is discharged in a divergent spray, the dimensions of the mark can be governed by regulating the distance between the spray nozzle and the surface to be marked at the conclusion of the discharging step. On the other hand, the intensity of the mark or the amount of liquid marking medium delivered at each operation is controlled and adjusted by the size of the pressure chamber formed by the piston and cylinder. This may be adjustably determined by any convenient means fixing the relative initial position of the piston and cylinder.

These and other features of the invention will be best understood and appreciated from the following description of a preferred embodiment thereof, selected for purposes of illustration and shown in the accompanying drawings in which:

Fig. 1 is a view in elevation of the device,
 20 Figs. 2 and 3 are views in longitudinal section through the barrel or cylinder showing the piston in two different positions,
 25 Fig. 4 is a sectional view of a conical pilot member, and
 30 Fig. 5 is a sectional view of the discharge nozzle.
 In its illustrated embodiment the device includes a handle 10 which may take the shape of a pistol grip and to which is rigidly secured a piston having a reduced shank 11 and an elongated body portion 12. A continuous passage runs through the entire length of the piston and this communicates with a passage (not shown) in the handle 10. A long cylinder 13 is telescopically and slidingly mounted on the piston. A seal between the two is provided by a pair of piston rings 14 herein shown as received in circumferential grooves at the outer end of the piston. The outer end of the piston is closed by a nozzle 15 having the discharge orifice.

45 The inner end of the cylinder 13 is externally threaded to receive adjustably a stop sleeve 16 having its end formed as a nut, and this is locked in position by a lock nut 17 which is also threaded onto the end of the cylinder. A spiral compression spring 18 encircles the shank 11 of the piston and is interposed between the face of the handle 10 and a washer which bears against the stop sleeve 16. A stop collar 19 is adjustably secured to the shank 11 of the piston. It is smaller in diameter than the coils of the spring 18 so that

it may move freely within the spring and thus serves to limit the compression of the spring and the displacement of the cylinder 13 with respect to the piston as will be readily seen by comparing Figs. 2 and 3. The shoulder 20 between the shank 11 and the body 12 of the piston serves to limit the outward movement of the cylinder under the actuation of the spring 18 by engaging the inner face of the stop sleeve 16. This limiting position is shown in Fig. 2.

A pressure chamber 21 is formed at the end of the piston within the cylinder and behind the discharge nozzle 15. When the cylinder 13 is displaced rearwardly on the piston, the volume of the pressure chamber 21 is reduced as will be apparent from comparing Figs. 2 and 3 of the drawings, and the charge forced out of it.

The atomizing nozzle 15 is provided with a threaded shank of reduced diameter fitting an internal thread formed at the end of the cylinder 13, and its body portion is fashioned as a nut so that the nozzle may be securely screwed in place. The body of the nozzle is hollow and its inner end is closed by a tubular nut 23 containing a valve seat which is normally closed by a ball 24, all as best shown in Fig. 5. In the outer end of the nozzle 15 is formed the outlet orifice 22. Flow through this orifice is controlled by a flanged stud 25 having a tapering outer face in which are formed skewed passages. The stud 25 and the ball 24 of the valve are normally held in place by a compression spring 26 which is interposed between them and which encircles the stem of the stud 25.

The passage in the handle 10 which communicates with the longitudinal passage in the piston terminates in a hollow stem 29 to which may be connected a flexible hose leading from a reservoir tank for the liquid marking medium that may be readily carried on the back of the operator of the marking device.

The outer end of the piston 12 is chambered, internally threaded and closed by a hollow threaded stud 30. At the inner end of this chamber is provided a seat for a check valve closed by a ball 31. Movement of the ball is limited by the inner end of the stud 30, the valve being permitted to open when suction is created in the suction chamber 21 and to close during the forced ejection of the marking medium from that chamber.

A flanged collar 32 is adjustably secured on the cylinder 13. To this is bolted a downwardly extending arm 33 which carries the pilot member of the device. In Figs. 1-3 this is shown as a pointed rod 34 which is rigidly secured to the arm 33 and extends a substantial distance beyond the end of the nozzle 15 and in parallel offset relation to the cylinder 13 so that pressure against the end of the pilot causes the rearward displacement of the cylinder upon its piston 12.

A pilot member of the alternative form is shown in Fig. 4 as a conical or flaring casing 35 disposed with its axis parallel to that of the cylinder 13. This is rigidly bolted to the flanged collar 32 and may be set to extend any predetermined distance beyond the nozzle in accordance with the size of the mark desired.

The operation of the device will be apparent from the foregoing description but may be summarized as follows. The operator first determines the location of the desired mark and then places the pointed end of the pilot rod 34 at the proper point against the surface to be marked. It will be apparent that this step may be carried

out with extreme accuracy. Having engaged the surface in this manner, the operator presses forwardly upon the handle 10, compressing the spring 18 and subjecting the fluid marking medium which has already been delivered to the chamber 21 to sufficient pressure to eject it as an atomized stream from the discharge orifice 22. During this operation the check valve 31 is closed and the outlet valve 24 is unseated by the fluid pressure behind it. The marking medium issues in the form of a conical spray, as indicated in Fig. 1 for example, and accordingly applies a circular mark to the surface. The size of the mark depends upon the setting of the pilot rod 34 and the amount of marking fluid used depends upon the initial volume of the pressure chamber 21 as determined by the setting of the stop sleeve 16. Having completed the marking step, pressure on the handle 10 is released and the spring 18 immediately restores the cylinder 13 to its initial position thereby expanding the pressure chamber 21, creating suction therein, and causing the chamber automatically to be refilled with the liquid marking medium. The check valve 31 is displaced during this refilling step. The operation may be repeated indefinitely as fast as the operator can re-locate the pilot rod 34 on surfaces to be marked, and immediately after each marking operation the pressure chamber is automatically refilled under the powerful suction of the expanding pressure chamber due to the action of the compression spring 18.

It will be noted that upon release of pressure on the pilot and drop of pressure in the pressure chamber 21, the ball 24 in the nozzle is immediately seated and thus prevents any possibility of drip from the nozzle. The ball also seals the nozzle and so prevents any air from being drawn into the pressure chamber.

The spring 26 holds back the ball 24 until enough pressure has been built up behind it to cause instant atomization of the marking fluid. None is permitted to escape except in the form of a very fine atomizing spray. This is delivered almost instantaneously and is not visible in the air but only evidenced by the spot as it appears on the surface to be marked. In actual practice 7000 perfect marks have been satisfactorily applied in an interval of 66 minutes.

The conical or flaring casing of the pilot member shown in Fig. 4 constitutes alternative means for limiting the divergence of the atomized spray and the size of the applied mark. This casing may be of any desired shape or may take the form of a stencil if desired. Preferably spacing lugs 36 are provided to hold the circular end of the casing slightly away from or above the surface to be marked and so obviate actual contact that might blur the mark.

Another form of stencil 37 is shown in Fig. 1 as supported by a spring 38 having a coil and an upstanding stem that may be inserted in any one of a series of vertical holes in the pilot rod 34, thus providing adjustment of the size of the stencil pattern. The stencil 37 may be in the form of a letter or any selected design.

Having thus disclosed my invention and described in detail illustrative embodiments thereof, I claim as new and desire to secure by Letters Patent:

1. A marking device comprising a piston having a passage therein for liquid marking medium, a cylinder telescopically mounted on the piston and forming therewith a chamber for a liquid charge, the chamber having a valve controlled

inlet port and an atomizing nozzle at the outer end of the cylinder, an elongated pressure transmitting pilot member adjustably secured to the cylinder and extending in parallel offset relation and clear of the nozzle to a fixed distance beyond the nozzle for contact with the surface to be marked, a spring normally advancing the cylinder on the said piston and thereby creating suction in the said liquid charge chamber, and means for determining the initial position of the cylinder on its said piston.

2. A marking device of the character defined in claim 1 in which the pilot member is conical in shape and controls by its adjusted position the size of the mark as applied by the device.

3. A marking device having a handle, a piston fixed in the handle and having a passage therein, a cylinder slidable on the piston and forming therewith a chamber for a liquid charge, a spring normally projecting the cylinder beyond the end of the piston by a predetermined distance and thereby creating suction in the chamber, a valve between the chamber and the passage in the piston, a spray nozzle at the outer end of the cylinder, and an elongated pilot rod secured to the cylinder and extending in parallel offset relation thereto a substantial distance beyond the spray nozzle and out of line therewith.

4. A portable marking device comprising a handle, a piston carried by the handle, a cylinder movably mounted on the piston, forming a pressure chamber therewith and having an atomizing nozzle at its outer end, a fluid supply passage leading through the piston to the pressure chamber and a valve in said passage, a pilot rod fast on the cylinder and extending beyond the end thereof, and a stencil carried by the rod and located in range of said nozzle.
